FUEL COMPOSITIONS

Anthony J. Revukas, Cranford, N. J., assignor to
 Tide Water Associated Oil Company, Bayonne,
 N. J., a corporation of Delaware

No Drawing. Application August 30, 1949.
 Serial No. 113,253

15 Claims. (Cl. 252—344)

1

The present invention relates to improved distillate fuel compositions and particularly, to such compositions adaptable for use as fuels for operation of diesel engines.

As is known to those skilled in the art, the presence of water in petroleum distillate fuels often results in emulsion formation especially when such water-containing fuels are subjected to agitation or other conditions promoting emulsification. Unless such emulsion formation is retarded or emulsions that have been formed are resolved so as to permit separation of water from the fuel, the water entering the system to be operated by the fuel deleteriously affects the performance of the system, particularly mechanisms therein of ferrous metals with which the water-containing fuel comes into contact. As an example, serious difficulties arise in marine operations when salt water, in amounts even as low as 0.01% by weight of a diesel fuel, enters diesel engines. The presence of water in the fuel enhances emulsification thereof and some of the emulsion normally passes through filtering mediums in the same manner as the fuel that has not been emulsified and, as a result, rapid engine failures often occur. Such failures are often due to corrosion of metal surfaces, as is manifested by surface pitting and formation of fatigue cracks on machined parts, to deleterious effects on fuel injectors resulting in broken or completely disintegrated check valve springs, to promotion of seizure of plungers in bushings and general corrosion of metal surfaces that are contacted by the water-containing fuel. Accordingly, the presence of water in petroleum distillate fuels, and particularly in diesel fuels, is highly undesirable and means are generally employed to separate the water, often in emulsified form, from the fuel. When the water present in the fuel is in emulsified form, one method for treating the emulsion to prevent water from entering the system is to break the emulsion and separate water from the fuel. As manufactured, petroleum distillates suitable for use as fuels are normally water free or contain not more than a trace of water and, hence, such distillates per se present little, if any, difficulty from emulsification unless extraneous water becomes admixed therewith. In illustration of such fuels, reference is made to the Navy Department Specification 7-0-2e of May 15, 1945, entitled "Oil, Fuel, Diesel," which, in listing the chemical and physical requirements for conformance therewith, sets forth that the diesel fuels must not contain more than a trace, as a maximum, of water and sediment. Nevertheless, and

2

in the handling of such fuels through pipe lines, storage thereof in tanks, and during transportation such as in seagoing tankers, extraneous water oftentimes becomes admixed with the fuel thereby providing difficulties inclusive of those aforesaid.

The present invention is based on a discovery that petroleum distillate fuels may be effectively inhibited against emulsification by dissolving in such fuels a small amount, sufficient to substantially reduce the tendency of the fuel to emulsify, of an amine such as is defined more fully hereinafter, thereby providing improved distillate fuel compositions that obviate or substantially minimize the occurrence of difficulties as aforesaid.

Broadly speaking, the amines embodied for use by the present invention may be illustrated by the following structural Formula 1:

wherein R^1 and R^2 are the same or different aliphatic groups having a sum of more than six carbon atoms, R^3 stands for a member from the group consisting of hydrogen, alkyl, aryl, alkaryl, and aralkyl radicals, and A is a phenol having at least one nuclear hydrogen atom replaced by a hydrocarbon group.

Amines suitable for practicing this invention and falling within the aforesigned structural formula may be prepared by various means known to those skilled in the art and, hence, it is not believed necessary to set forth a detailed procedure for preparation thereof. However, and for purposes of illustration, methods suitable for preparation of such amines are included in disclosures such as U. S. Patent No. 2,363,134 (McCleary) and more specifically in accordance with the procedure in Example I, page 3, column 1 of that patent, as well as the procedure set forth in my copending application Serial No. 787,037 filed November 19, 1947 (now U. S. Patent No. 2,489,672 issued November 29, 1949). As is apparent from the disclosure in the aforesaid patent and copending application, a suitable method for preparation of amines as contemplated for use herein involves the reaction between a suitable phenol, an aldehyde and a secondary amine.

In a specific and preferred aspect, the invention embodies use of amines such as may be prepared by reaction of a secondary alkylamine with form-

aldehyde and a suitable phenol to form amines of the following structural Formula 2:

wherein R¹ and R² are alkyl radicals containing a sum of more than six carbon atoms, and A is a phenol having at least one nuclear hydrogen atom replaced by a hydrocarbon group. Secondary alkylamines (containing a sum of more than six carbon atoms) suitable for preparing the compounds of the aforesaid structural formula include dibutylamine, di-2-ethylhexylamine, di-laurylamine, and the like, and suitable phenols include cardanol, para-tert. amyl phenol, penta-decyl phenol and the like. More specific illustrations of amines falling within the aforesaid structural formula and suitable for practicing this invention include diamylaminomethyl para-tert.-amyl phenol, diamylaminomethyl, 2,4-di-amylphenol, dibutylaminomethylcardanol, diamylaminomethylcardanol, diamylaminomethylpentadecylphenol, di-2-ethylhexylaminomethylcardanol, di-laurylaminomethylcardanol, and the like.

Although compounds of the aforesaid Formula 2 are particularly preferred, other amines that may be employed include compounds of the aforesaid structural Formula 1 wherein R³ may be an alkyl, aryl, alkaryl or aralkyl radical. As compared to the aforesaid structural Formula 2 wherein by use of formaldehyde in the reaction the nitrogen atom is linked to the phenol group by a methylene group, the use of higher aliphatic aldehydes during the reaction provides amines of structural Formula 1 wherein R³ is an alkyl group. Thus, by use of acetaldehyde, the group

links the nitrogen atom to the phenol grouping; and when an aldehyde such as propionaldehyde is used, the linking group is

Similarly, when still higher aliphatic aldehydes such as butylaldehyde, octylaldehyde, etc. are employed, R³ represents an alkyl group containing a correspondingly higher number of carbon atoms, and when R³ is represented by radicals such as aryl, alkaryl, and aralkyl, the amines of aforesaid structural Formula 1 may be prepared by use, for the reaction, of aldehydes such as benzaldehyde, methyl benzaldehyde, ethyl benzaldehyde, phenylacetaldehyde, and the like.

In order to further describe my invention, several illustrative, but not limitative, embodiments thereof are set forth hereinafter showing the effective demulsifying properties imparted to petroleum distillate fuels by use of tertiary amines as embodied for use herein. In the examples set forth herein, the test compositions were prepared by dissolving the tertiary amine in the fuel, mixing the thus prepared solution with either distilled or synthetic sea water, and subjecting the resulting compositions to the defined test procedures to determine demulsifying characteristics.

EXAMPLE I

A diesel fuel of specification 7-0-2e grade and having an A. P. I. gravity of 36.1 and a viscosity of 35.7 SUS at 100° F. was subjected to the following Procedure A and, under the conditions thereof, 35 minutes was required for demulsification. However, by use of the same fuel oil under the same test conditions except that 0.1% of diamylaminomethylcardanol had been added to the fuel oil, the emulsion was completely resolved within 20 minutes.

Test Procedure A

The apparatus consists of a motor-driven mixer and a seamless copper tubing vessel 12 inches in height having an inside diameter of 2.5 inches. A pet cock is situated in the vessel so that the center line of the pet cock is at the 100 milliliter level of the copper vessel. 190 milliliters of the fuel oil under test and 10 milliliters of synthetic sea water are poured into the mixing vessel and warmed to 100° F. The composition in the vessel is then stirred at 7000 R. P. M. for 5 minutes and 100 milliliters of the emulsion drained off by means of the pet cock into a centrifuge tube while stirring is maintained. The emulsified sample in the 100 milliliter centrifuge tube is whirled at 2600 revolutions per minute for 5 minutes and then about 6 milliliters are poured into a 10 milliliter comparator tube having two flat sides. This sample is compared with the original test composition for clarity. If both compositions are equivalent in clarity, the result is recorded as "5 minute demulsification time." If the two samples are dissimilar in clarity, the centrifuged sample is returned to the centrifuge tube and again whirled at 2600 revolutions per minute for 5 minutes, followed by another comparison for clarity. The procedure is continued until an equivalent in clarity is obtained, and the total time recorded as "demulsification time."

In the handling of petroleum distillate fuels, contamination thereof often results due to the presence of contaminants in pipe lines, storage tanks, and the like. For example, in the transferring of such fuels through pipe lines, hoses and the like, the fuels are oftentimes contaminated by admixture with adventitious materials that may have previously been handled through the same lines, etc. For example, such contamination often occurs in marine operations wherein fuels, such as diesel fuels, may be contaminated with bunker fuel oils and the like. The presence of such contaminants in petroleum distillate fuels may be highly undesirable in that when water becomes admixed with the fuel, the bunker fuel oils may also tend to promote emulsification, thus making it even more difficult to separate the water from the fuel composition. However, by practicing the present invention, petroleum distillate fuels contaminated with such contaminants having a tendency to enhance emulsification may also be effectively imparted with emulsion-inhibiting properties to thereby facilitate removal of water from the fuels as is illustrated by the following Example II:

EXAMPLE II

A diesel fuel containing about 50% by volume of synthetic sea water emulsified badly when contaminated with about 0.5% by weight of a straight run paraffinic bunker fuel. When tested under the conditions of the following Procedure B, such a contaminated fuel oil composition possessed 10 milliliters in emulsified form after

66 minutes. However, by practice of the present invention, and adding 0.2% by weight of diamylaminomethylcardanol to the contaminated diesel fuel, highly improved demulsification occurred in that only 2 milliliters of emulsion were present at the 60 minute reading.

Test Procedure B

The apparatus employed comprises a motor-driven mixer, a 100 milliliter graduate, and a constant temperature bath.

Eighty ml. of the test composition consisting of 40 ml. of test oil and 40 ml. of distilled water or synthetic sea water are poured into the graduate and the test composition is then stirred for 5 minutes at 1500 revolutions per minute while maintaining the 130° F. temperature whereby the composition is emulsified. After the 5 minute stirring is complete, the emulsified composition is maintained at 130° F. without additional agitation. The test composition is observed at 5-minute intervals up to a 60-minute period. At each interval, it is noted whether the emulsion has been completely separated into a layer of water and a layer of oil, or whether an oil-water emulsion is still present. If the emulsion has not been completely broken, the amount that is present is recorded as "milliliters of cuff" by direct reading on the graduate at 30 minute and 60 minute readings. When emulsion is present, the test composition comprises a bottom layer of water, a top layer of oil and an intermediate layer of emulsion.

EXAMPLE III

As another example, a light hydrocarbon diesel fuel of Navy Specification 7-0-2e grade was subjected to test in accordance with the aforesaid Procedure B using a temperature of 77° F. When either synthetic sea water or distilled water was employed, 2 to 4 milliliters of emulsion existed at the 30 minute reading under the conditions of the test procedure. However, by use of the same fuel oil containing 0.1% of diamylaminomethylcardanol and, irrespective of whether synthetic sea water or distilled water was employed, the fuel oil composition was completely demulsified in 1½ minutes.

Although the foregoing examples set forth use of specific demulsifying agents and concentrations thereof employed, use thereof has been made for illustrative and not limitative purposes as the invention embodies use of demulsifying agents falling within the generic structural formula as aforesigned. As to the concentration of demulsifying agent employed, the concentration thereof may be varied depending upon various factors as, for example, the susceptibility of the petroleum distillate fuel to emulsify and the degree of demulsification desired. For most purposes, suitable results are obtained by use of the demulsifying agent in amounts ranging from about 0.02 to about 0.1% based on the weight of the fuel. However, it is within the scope of the invention to employ the demulsifying agent in amounts other than the aforesaid range as, for example, from about 0.005 to about 1.0% and even higher, e. g., 2%, as for particular fuel oils the lower concentrations show suitable improvement in demulsifying characteristics whereas with certain more readily emulsifiable fuels, the higher concentration may be more desirably employed.

In practicing my invention, the contemplated amine demulsifiers may be added in desired amounts to the fuel oils that have emulsified as

a result of water having become admixed therewith or may be added to the fuel oil to suppress emulsification thereof when such oils are subsequently exposed to conditions promoting emulsification by admixture of water therewith. For such purposes, the demulsifiers of the present invention may be employed per se, in mixtures thereof, or in combination with a suitable vehicle e. g., a petroleum fraction, to form a concentrated solution or dispersion for addition to the fuels to be treated. For example, when it is desired to add the demulsifying agent in the form of a concentrated solution or dispersion, it is preferable that such a solution or dispersion be prepared by employing a vehicle that is compatible with and does not deleteriously affect the performance of the petroleum distillate fuel to be treated. Hence, particularly suitable vehicles for preparing concentrated solutions or dispersions of the demulsifying agents include petroleum fractions similar to or identical to the petroleum distillate fuel to be treated in accordance with this invention. In illustration, such concentrates may comprise a petroleum distillate or other suitable liquid hydrocarbon in admixture with a demulsifier as embodied herein and wherein the demulsifier is present in an amount of about 10 to 75% based on the weight of the concentrate. As specific illustrations, such concentrates may comprise a suitable hydrocarbon vehicle, e. g., diesel fuels, kerosenes, and other mineral oil fractions, in which there is dissolved or dispersed a demulsifier such as diamylaminomethyl cardanol in amounts varying from about 10 to 75% by weight of the concentrate, and, in still more specific illustration, a suitable concentrate comprising about 50% by weight of diamylaminomethyl cardanol in admixture with a petroleum hydrocarbon of diesel fuel grade.

The term "synthetic sea water," as used herein, is intended to include a composition prepared by dissolving the following compounds and concentrations thereof in a sufficient amount of distilled water to make up one liter of solution:

	Grams
Magnesium chloride ($MgCl_2 \cdot 6H_2O$)	11
Calcium chloride ($CaCl_2$) anhydrous	1.2
Sodium sulfate (Na_2SO_4)	4.0
Sodium chloride ($NaCl$)	25.0

The present application is a continuation-in-part of my copending application Serial No. 718,599, filed December 26, 1946 (now abandoned).

Although the present invention has been described in conjunction with certain preferred embodiments thereof, those skilled in the art will readily recognize that variations and modifications can be made. Such variations and modifications are to be considered to be within the purview of the specification and the scope of the appended claims.

I claim:

1. As a new composition, a petroleum distillate fuel having dissolved therein a small amount, sufficient to suppress the tendency of said fuel to emulsify, of a compound having the formula:

wherein R^1 and R^2 are aliphatic groups having a sum of more than six carbon atoms, R^3 is a member from the group consisting of hydrogen, alkyl, aryl, aralkyl and alkaryl radicals, and A

is a phenol having at least one nuclear hydrogen atom replaced by a hydrocarbon group.

2. A composition, as defined in claim 1, wherein the defined compound is employed in an amount of about 0.005 to about 2% based on the weight of the fuel.

3. As a new composition, a petroleum distillate fuel having dissolved therein a small amount, sufficient to substantially suppress the tendency of said fuel to emulsify, of a compound of the formula:

wherein R^1 and R^2 are alkyl radicals containing a sum of more than six carbon atoms, and A is a phenol having at least one nuclear hydrogen atom replaced by an aliphatic group.

4. A composition, as defined in claim 3, wherein the defined compound is dissolved in the fuel in an amount of about 0.005 to 2% based on the weight of said fuel.

5. A composition, as defined in claim 3, wherein the petroleum distillate fuel is a diesel fuel.

6. A composition, as defined in claim 3, wherein the defined compound is a dialkylamino-methylcardanol.

7. A composition, as defined in claim 3, wherein the defined compound is diethylaminomethyl-cardanol.

8. A method for resolving an emulsion formed by a petroleum distillate fuel with water which comprises adding to said emulsion a small amount, sufficient to resolve said emulsion, of a compound having the following formula:

wherein R^1 and R^2 are aliphatic groups having a sum of more than six carbon atoms, R^3 is a member from the group consisting of hydrogen, alkyl, aryl, aralkyl and alkaryl radicals, and A is a phenol having at least one nuclear hydrogen atom replaced by a hydrocarbon group.

9. As a concentrate, adaptable for use as an emulsification-inhibiting additive for liquid hydrocarbons, an oil-soluble amine of the following formula in admixture with a petroleum dis-

tillate fuel, said amine being present in an amount of about 10 to about 75% based on the weight of the concentrate and having the following formula:

wherein R^1 and R^2 are aliphatic groups having a sum of more than six carbon atoms, R^3 is a member from the group consisting of hydrogen, alkyl, aryl, aralkyl and alkaryl radicals, and A is a phenol having at least one nuclear hydrogen atom replaced by a hydrocarbon group.

10. A method, as defined in claim 8, wherein R^3 is hydrogen.

11. A method, as defined in claim 8, wherein A is a phenol having at least one nuclear hydrogen atom replaced by an aliphatic group.

12. A method, as defined in claim 8, wherein R^3 is hydrogen and A is a phenol having at least one nuclear hydrogen atom replaced by an aliphatic group.

13. A concentrate, as defined in claim 9, wherein R^3 is hydrogen.

14. A concentrate, as defined in claim 9, wherein A is a phenol having at least one nuclear hydrogen atom replaced by an aliphatic group.

15. A concentrate, as defined in claim 9, wherein R^3 is hydrogen and A is a phenol having at least one nuclear hydrogen atom replaced by an aliphatic group.

ANTHONY J. REVUKAS.
